UNITED STATES PATENT OFFICE.

ASA E. LINENDOLL, OF NORWALK, OHIO.

ADJUSTABLE SHELL.

Application filed December 16, 1926. Serial No. 155,294.

My invention has for its object to provide a shell member that is so constructed that it may be readily modified so as to receive therein and fit cylindrical bodies of different sizes. It is particularly adapted for use in connection with cylindrical bodies that follow standard sizes. Thus my invention provides a means whereby a shell of any form may be readily fitted to any other of a plurality of sizes of pipes that follow a standard rule with reference to their different diameters.

The invention is particularly advantageous when used in connection with automobile heaters wherein a shell is located around an exhaust pipe. Such pipes vary in sizes according to a recognized standard and the shell member embodying my invention is so constructed that it may be readily formed so that it will fit at its ends, around the pipe and form a chamber between the pipe and the wall of the heater. This provides a space wherein air may be, by movement of the car, forced between the exhaust pipe of the automobile, a suitable outlet being provided for directing the air that is heated in the chamber within the heater into the car.

The invention may be contained in structures of different forms and used for a great variety of purposes. To illustrate a practical application of the invention, I have selected a structure containing the invention, and shall describe it hereinafter. The structure selected as an example of the different embodiments of my invention is shown in the accompanying drawings.

Figure 1 of the drawings illustrates a side view of a heater that embodies my invention and shows the position in which it may be placed according to the shape or form of the exhaust pipe of an automobile. Figure 2 illustrates the heater located in a second position. Figure 3 is an end view of the heater when in the position shown in Figure 2. Figure 4 is a view of a longitudinal section taken on the plane of the line 4-4 indicated in Figure 3. Figure 5 is a view of a transverse section taken on the plane of the line 5-5 indicated in the Figure 4. Figure 6 is a top view of a register which may be opened or closed to allow the heated air from the heater to enter the interior of the automobile. Figure 7 is a view of a section taken on the plane of the line 7-7 indicated on the Figure 6.

In the arrangement shown in Figure 1,

the heater 2 which is made in the form of a shell is placed on the exhaust pipe 3 which is cylindrical in form at a point where the exhaust pipe slopes upward towards the engine. The heater 2 is provided with a scoop-shaped inlet 4, the heater having an opening 5 at one end covered by a cowl or visor 6 or other air collector. In the movement of the car, the inlet 4 will catch the air and it will be directed into the heater and along the exhaust pipe 3 and out through an outlet, 8. The outlet is connected by a suitable pipe, such as, the pipe 9 with a register 10. The register 10 may be provided with a flange 11 for receiving the end of the pipe 9. The flange 11 may extend through the floor boards 12 of the automobile and thus the air which is heated by the heater will be forced through the heater and into the car body.

The heater is so constructed that either end may be located towards the engine, the cowl 6 being made removable or reversible so as to be turned towards the forward end of the car to catch the air when the car is in motion. Such an arrangement is shown in the Figure 2 where the intake end of the heater is located to the rear of the point of the location of the register. The heater is also provided with an opening, 14 that is formed in the heater shell at a point diametrically opposite to the opening 5. The opening 14 may be closed with a cover plate 15 that is secured by screws 16 in the same manner that the cowl 6 is secured by the screws 17 to the heater. Thus, when it is desired to locate the cowl 6 on the same side of the heater that the outlet 8 is located on, the cover plate 15 and the cowl 6 may be interchanged and secured to the heater. Also the cowl 6 may be pointed in either direction with reference to the center of the heater, it being understood, however, that the cowl, 6 is always pointed towards the front of the car, that is, so as to receive the air under the pressure that is produced by the movement of the automobile, or more particularly, by the movement of the cowl.

In order to adapt the heater for the different sizes of exhaust pipe, which follow accepted standards, the ends of the heater are provided with stepped portions 20. The portions of the inner and outer surfaces of the stepped portions are likewise stepped relative to each other. The inner cylindrical surfaces such as the surfaces 21 overlap

the exterior cylindrical surfaces such as the surfaces 22. The distance between these surfaces is very small compared to the thicknesses of the portions of the stepped ends of the heater. The exterior plane surfaces, such as surfaces 23, are located parallel to the interior plane surfaces, such as the surfaces 24, and the planes of the outer plane surfaces are located nearer the center of the heater than the planes of the inner plane surfaces of the juxtaposed stepped portions that are smaller in diameter. As, for example, the step 25 is defined by the cylindrical surfaces 21 and 22, and by the plane surfaces 23 and 24. The step 26 is defined by similar surfaces and in the same way. The step 25 is smaller in diameter than the step 26. The inner plane surface 24 of the step 25 is located outside the plane surface 23 on the step 26, with respect to the center of the heater. When, therefore, it is desired to fit the heater to a certain size of pipe all that is required is to saw through the thin connecting web between the cylindrical surfaces 21 and 22 in order to remove the steps that have inner diameters that are smaller than the pipe to which the heater is to be fitted. This may be used in connection with a great variety of shells where they are to be fitted to cylindrical bodies of different sizes.

The steps that are to be removed, in order to produce a fit between the shell and the cylindrical member, such as the pipe, may be cut off by a saw or by one or two blows of a chisel. This may be readily done in view of the fact that the webs that join the portions of the stepped flange at each end of the heater are relatively quite thin. When the webs are sawed, the inner and outer plane surfaces 23 and 24 form a guide for the saw, the distances between the planes of these plane surfaces being at the proper distance to act as guides for an ordinary iron saw. The heater may be provided with inwardly extending ribs, 30 in order to aid in directing air through the heater. Also the flange 11 of the register may be connected to a plate 31 and the plate 31 may be covered

with a plate 32 having a plurality of openings 33. The two plates 31 and 32 provide means for inclosing a disk or cover plate, 34. The flange 11 may be located at one end of the plate 31 and the disk 34 may be shifted between the plates 31 and 32 to open and close the end of the pipe 9 which is connected to the flange 11. If desired the plate 32 may be suitably formed to present an attractive or decorative appearance.

In order to readily shift the disk or cover plate 34, the plate 32 may be provided with a slot 35 and the plate 34 may be provided with a pin 36 that extends through the slot 35. A washer, 37, may be located on the pin 36 and a spring 38 may be located between the cover plate 34 and the washer 37 so as to hold the cover plate 34 against the plate 31 and thus to tightly close the passage-way from the heater and shut off the heat that is conveyed to the interior of the car by the movement of the air into the car when the cover plate 34 is open.

I claim:

1. In combination, a shell member and a cylindrical member, the shell member having a stepped circular flange, the steps joined by relatively thin cylindrical webs whereby stepped portions may be removed by separating the steps from the body of the shell along the webs leaving a stepped portion whose inner diameter is substantially the same as that of the cylindrical member.

2. In an automobile heater a shell having end portions fitting the exhaust pipe of the automobile engine, the body of the shell spaced from the pipe to form a chamber between the wall of the shell and the pipe, one end of the shell having openings located diametrically opposite each other, an interchangeable plate and an air collector for covering the openings, the other end of the shell having an opening, and a register connected with the last named opening.

In witness whereof I have hereunto signed my name to this specification.

ASA E. LINENDOLL.
